Hans Reinhard Fehling, Zug, Switzerland, and Alfred Dennis Street, Pinner, Middlesex, England, assignors to I.R.C. Limited, London, England, a company of Great Britain

Filed Mar. 9, 1961, Ser. No. 64,201

Term of patent 14 years

(Cl. D74—17)

FIG. 3

FIG. 1 is a side view of a writing instrument embodying the present design;

FIG. 2 is a top, perspective view thereof; and

FIG. 3 is a bottom perspective view thereof.

The broken line illustrations on the drawing indicate an ink cartridge which is secured in an open groove on top of the barrel as shown in FIG. 2. The essential features of the design reside in the portions shown in solid lines.

We claim:

The ornamental design for a writing instrument, as shown and described.
